UNITED STATES PATENT OFFICE.

LOUIS C. STUKENBORG, OF BIRMINGHAM, ALABAMA.

HOSE-SUPPORTER.

1,070,557.

Specification of Letters Patent. Patented Aug. 19, 1913.

Application filed April 19, 1912. Serial No. 691,878.

To all whom it may concern:

Be it known that I, LOUIS C. STUKENBORG, a citizen of the United States of America, and resident of Birmingham, in the county 5 of Jefferson and State of Alabama, have invented certain new and useful Improvements in Hose-Supporters, of which the following is a specification.

This invention relates to a garment supporting device and particularly to a garment 10 clasp designed for use in connection with garment supporters, the invention being particularly adapted for use in connection with hose supporters.

15 An object of the invention is to provide a garment clasp of the type shown in my patent, numbered 923,600, bearing date of June 1, 1909, the present invention being an improvement on the garment clasp described 20 and claimed in the said patent.

An object of this invention is to provide a 25 clasp of the character noted, the same being provided with novel means for anchoring and retaining a cushion designed to increase the friction between the garment and the clasp.

A further object of this invention is to 30 provide the clasp with recesses or seats, one of which is formed in the outer edge thereof and the other of which is produced by the formation of the notch therein for the reception of the garment.

With the foregoing and other objects in view, the invention consists in the details of 35 construction and in the arrangement and combination of parts to be hereinafter more fully set forth and claimed.

In describing the invention in detail, reference will be had to the accompanying 40 drawings forming part of this specification wherein like characters denote corresponding parts in the several views and in which—

Figure 1 illustrates a view in elevation of a garment support with the clasp applied 45 thereto; Fig. 2 illustrates a detail view of the clasp with the cushion omitted; and Fig. 3 illustrates a sectional view on the line 3—3 of Fig. 2.

In these drawings, I have shown a clasp 50 having an eyelet or loop 4 for the reception of a webbing or other agent by which the clasp is connected to a body-engaging member, that portion of the clasp containing the eyelet or loop being increased in area as 55 compared with the corresponding portion in

the patent in order to give increased bearing surface for the hand of the operator in attaching the grip to the hose.

The clasp is struck from a single piece of metal and the lower part thereof is provided 60 with a slot forming the jaws 5 and 6 which are preferably approximately parallel, one of the said jaws being integral with the portion of the clasp containing the slot 4, whereas the other jaw being integral with 65 the first mentioned jaw is supported thereby. The free end of that portion of the clasp containing the jaw 6 is preferably curved to form an eye 7 just as the similar part is described in the patent. The end of the clasp 70 remote from the suspending means or the portion containing the loop or eyelet 4 is notched or recessed as shown at 8 forming a seat for a cushion 9, which cushion extends through the slot or opening between the jaws 75 5 and 6 and through the side 8 and may be in the form of a rubber band which can be applied by passing the same over the free end of the jaw 6. The proportions of this clasp are slightly changed as compared with 80 the clasp shown in the patent, in that the portion of the clasp between the lower or inner end of the slot and the edge of the clasp is slightly longer to compensate for the reduction in strength of the clasp due to the 85 formation of the seat or notch 8 in the end thereof. The clasp of this invention, therefore, will prove as satisfactory, so far as strength and durability are concerned, as the clasp disclosed in the patent, but it will have 90 the added feature heretofore indicated of providing a cushion to increase the friction between the garment and the clasp to prevent tearing or wear on the fabric of the garment being supported.

95 I claim—

A garment fastener comprising a member having a slot, said slot forming jaws, the portion connecting the jaws being notched, said jaws adapted to clamp a garment therebetween, a circular elastic cushioning member held by said notched portion, said cushioning member adapted to prevent slipping of the garment clamped between the jaws.

100 In testimony whereof, I affix my signature 105 in the presence of two witnesses.

LOUIS C. STUKENBORG.
